W. E. DANGERFIELD

CURTAIN HANGER

Filed April 5, 1923

Inventor:
William E. DANGERFIELD
Hazard & Miller
Attorneys.

UNITED STATES PATENT OFFICE.

WILLIAM E. DANGERFIELD, OF PASADENA, CALIFORNIA.

CURTAIN HANGER.

Application filed April 5, 1923. Serial No. 630,032.

To all whom it may concern:

Be it known that I, WILLIAM E. DANGERFIELD, a citizen of the United States, residing at Pasadena, in the county of Los Angeles and State of California, have invented new and useful Improvements in Curtain Hangers, of which the following is a specification.

This invention relates to curtain and drapery supports, and has for an object to provide a support adapted to be mounted in combination with a casement window, so that curtains and drapes will be automatically swung to a position over the inside of the window sash when the window is closed, and will also be thrown open automatically with the inward movement of the casement sash.

It is an object to provide a curtain and drape supporting means which will be adjustable consonant with movement of the sash and therefore eliminate manual adjustment of the curtain supports before and after the window is closed or opened. Another object is to provide a curtain and drape supporting means of simple and inexpensive form of construction, and which can be readily adapted to a given window.

Other objects and advantages will be made manifest in the following specification of an embodiment of the invention illustrated in the accompanying drawings, wherein

Figure 1 is an inside elevation of a portion of a wall in which is arranged a casement window, the sash of which is shown closed.

Fig. 2 is a plan of the fixture.

Fig. 3 is a perspective the fixture having a single bracket arm.

The present invention consists of means upon which may be readily supported a curtain and drapes, and which means includes a bracket part adapted to be fixedly attached to the window frame F, and also includes parts removably attached to the window sash S, so that the curtain C and the drapes D will be moved concurrently with the opening and closing of the sash S.

In its illustrated form, the invention includes a rod or tube 2, one end of which is connected to swing on a vertical axis as by a pin 3, carried by a fixed bracket 4 projecting forwardly from the frame F. The swinging end of the rod 2 is provided with

an inwardly bent portion 2^a and this, in turn, is provided with a bar portion 2^b which is disposed parallel to the rod 2. The bar 2^b is slidably and readily detachably connected with the swinging upper corner of the sash S, as by a bracket 5, fixed by screws or pins 6 to the top of the sash S. The top of the bracket 5 is provided with a semi-circular seat 7, into which the rod 2^b can be readily seated, and on which the rod 65 will slide as the sash S is opened, due to the eccentricity of the hinges H of the sash and the pivot 3 of the curtain rod 2. From this it will be seen that as the sash S is opened, the curtain rod 2 will be swung out away 70 from the frame and the curtain can be thrown around with the sash as this is adjusted in fully open position back against the wall W.

A present predominant decorative fashion 75 consists in utilizing drapes D inside of the curtains C (only fragments of which drapes and curtains are indicated). For the purpose of mounting the drape D so that it will also swing open and closed with the sash S, I provide a drape rod 10, having a vertical pivot 11 on the projecting end of a bracket 12, which may be provided fixedly on a plate 13 which carries the bracket 4. The drape rod 10 is of precisely similar design 80 to the curtain rod 2 and has, therefore, an inside parallel bar 10^b by which slidable connection is made with the sash S.

Preferably, the slidable connection of the drape carrying device is obtained by means 90 of a seat-forming device 15, which is provided on or attached to the curtain carrier 2, so that, as the curtain carrier swings with the sash S, the drape carrier 10 will also swing. The seats 7 and 15 not only provide 95 for a sliding connection as between the carrying members 2 and 10 and the sash S, but they further provide means from which the curtain and drape carriers can be readily lifted for independent movement.

The carrying members 2 and 10, as above indicated, may be made of solid rods or tubular material, and are substantially free from obstructing portions so that the hems of the curtains and drapes can be readily reeved on to and from the rods; the seat device 15 being preferably detachably provided on the rod 2^b so as to provide for the mounting and dismounting of the curtain.

It will be seen that by my form of cur-

tain holder it is possible to extend curtains and drapes entirely across the window sash and its casing or frame, and also extend the curtains to the top of the window frame, and yet provide for the swinging of the curtains and drapes with the window sash.

Further embodiments, modifications and variations may be resorted to within the principle of the invention.

10. What is claimed is:

1. A curtain or drape supporting means including a rod-like member pivotally attached to a support at one end said rod like member having its other end bent upon itself, and a support adapted to be attached to a swinging element and upon which said bent portion is slideably mounted.

2. A curtain or drape supporting means including a rod-like member pivotally attached to a support at one end and having a support adapted to be attached to a swinging element, and upon which the said member is adapted to be slideably mounted, said member having a portion to receive the curtain or drape, and having also a portion to rest on its supporting bracket so that the said member can swing with the swinging element without changing the position of the drapery on its carrying portion.

3. A curtain or drape hanger comprising a bracket fixture, a plurality of curtain or drape rod-like members pivotally connected to the bracket fixture, and a supporting bracket adapted to be fastened to a swinging element and upon which one of said members is adapted to be slideably mounted so that the said member will swing open and closed with the opening and closing movement of said element.

4. A curtain or drape hanger comprising a bracket fixture, a curtain or drape rod-like member pivotally connected to the bracket fixture, and a supporting bracket adapted to be fastened to a swinging element and upon which said member is adapted to be slideably mounted so that the said member will swing open and closed with the opening and closing movement of said member, said member being adapted to be lifted readily from, and disposed upon, the supporting bracket and be moved independently of the swinging element.

5. A curtain and drape hanger comprising a bracket fixture, a plurality of rod-like members pivotally connected at one end of each to said bracket fixture, said members having portions reversely bent upon themselves and means for slideably connecting said reversely bent portions to a swinging element whereby the said members will be moved concurrently with the swinging element when attached thereto.

6. A curtain and drape hanger comprising a bracket fixture, a plurality of rod-like members pivotally connected at one end of each to said bracket fixture, and means for slideably connecting said members to a swinging element and whereby the said members will be moved concurrently with the swinging element when attached thereto, said means including a supporting bracket attachable to the swinging element and supporting connection between the said members.

In testimony whereof I have signed my name to this specification.

WILLIAM E. DANGERFIELD.
